UNITED STATES PATENT OFFICE.

WILLIAM S. HARLEY, OF MILWAUKEE, WISCONSIN.

OIL-DISTRIBUTING MECHANISM.

1,108,904.

Specification of Letters Patent.

Patented Sept. 1, 1914.

Application filed May 18, 1914. Serial No. 839,397.

To all whom it may concern:

Be it known that I, WILLIAM S. HARLEY, a citizen of the United States, and resident of Milwaukee, in the county of Milwaukee, and State of Wisconsin, have invented certain new and useful Improvements in Oil-Distributing Mechanism; and I do hereby declare that the following is a full, clear, and exact description thereof.

10 My invention has for its object to provide a simple, economical and efficient oil-distributing means for lubricating machine elements, the same being so constructed and arranged that by utilizing a novel adjustable pump mechanism the oil feed is predeterminedly regulated in proportion to economic consumption.

With the above and other objects in view the invention consists in what is herein 20 shown and described with reference to the accompanying drawings and subsequently claimed.

In the drawings Figure 1 represents a sectional front elevation of an oil distributing mechanism embodying the features of my invention, the section being indicated by lines 1—1 of Figs. 2 and 3; Fig. 2, a sectional plan view of the same, the section being indicated by line 2—2 of Fig. 1; Fig. 30 3, a detailed sectional plan view through the mechanism, the section being indicated by line 3—3 of Fig. 1; Figs. 4 and 5, detailed cross-sections through a valve mechanism employed in carrying out my invention, the 35 sections being indicated by lines 4—4 and 5—5 of Fig. 1, and Fig. 6, a detailed longitudinal sectional view through the delivery port and sight feed basin, the section being indicated by line 6—6 of Fig. 1.

40 In the exemplification of my invention I have shown the same applied to the face-plate of a gear-casing fragmentarily illustrated, which gear-casing carries a train of gears constituting part of a motorcycle 45 transmission from the source of power, all of which machine elements form no part of my present invention.

Referring by characters to the drawings, 1 represents the face-plate of a gear-casing 50 2, which plate constitutes a housing for a rotatory cylindrical valve-plug 2, the said valve-plug being fitted within a vertically disposed chamber 2' that is provided with a jacket lining 2'', within which the valve-plug has snug revolving fit. The upper and 55 lower ends of the chamber 2' are provided

with axially alined cones 3, 3', respectively, which form end journals for the valve-plug, the upper cone 3 constituting a cap-closure for the chamber, whereby the valve-mechanism is rendered accessible. The lower end of the valve-plug 2 is formed with a reduced neck that terminates with an eccentric head 4, which head constitutes the driving element for a reciprocative pump piston 5, the 60 same being mounted within an obliquely disposed jacketed well 6, which well intersects the bottom portion of the valve-chamber 2 to form a communicating pocket. The lower end face of the pump piston 5 is positioned to partially overlap the eccentric face of the valve-head 4 and is held in engagement with the eccentric face by a coiled spring 7, which spring is incased within the upper portion of the well that constitutes 70 an oil-reservoir. The spring is interposed between a shouldered upper end of the pump piston and a cap 8, which cap forms a closure for the mouth of the oil reservoir, as shown. That portion of the lower face of 80 the piston which is clear of the valve-head 4, as shown, is arranged to be engaged by an adjustable member, which member is in the form of a screw 9 that is in threaded union with the bottom of the well pocket. Thus 85 said screw may be adjusted to raise or lower the pump piston in opposition to its spring resistance, whereby the stroke of said pump piston is regulated, the maximum stroke of the same being in proportion to the pitch 90 of the eccentric face of the valve-plug head.

Motion is imparted to the valve-plug by means of a toothed section or pinion 10 that is cut into the body of the valve-plug above its neck portion and this pinion meshes with 95 a worm 10', which worm is carried by the hub of a gear-wheel 11, the said hub being journaled upon a stud 12 that is supported by the rear wall of the gear-casing 2. The gear-wheel 11, as shown in Fig. 2, constitutes one of a train of gears 11', which gear-train is driven from a suitable source of power, not shown, whereby motion is incidentally transmitted to the rotary valve-plug.

Oil is fed to the valve chamber 2' from a gravity feed-pipe 13 through an inlet port 14, which delivery port is adapted to register with a peripheral segmental delivery groove 15 in the valve-plug, the said groove being 110 provided with a feed-aperture 15' that communicates with a longitudinally disposed

receiving and delivery duct 17 that is cored in the valve-plug, the mouth of the duct being closed by the cone-bearing 3. The valve-plug is also provided with a similar segmental discharge groove 18 communicating with the receiving and delivery duct 17, as best shown in Fig. 3. The groove 18 is of greater length than the groove 15, being extended through approximately one-half the circumference of the plug, while the delivery groove 15 is approximately one-quarter of the circumference of the same, as best shown in Fig. 4. The discharge groove 18 is arranged to effect registration once in each revolution of the plug with a discharge port 19, which discharge port communicates with a sight feed basin 20 formed in the face of the plate 1. The front wall of the basin is formed by a glass disk 21 that is secured by suitable gaskets and a gland in threaded union with said basin. The bottom of the basin below the mouth of the discharge port 19, is provided with a flow mouth 22, as best shown in Figs. 1 and 6, which flow mouth communicates with the interior of the gear-casing, whereby oil is distributed to the desired machine elements. By interrupting the discharge port with the sight feed basin mentioned the efficiency of the flow of oil can at all times be observed. The valve-plug is also provided with a receiving and delivery groove 23, which groove, as best shown in Figs. 1 and 5, extends continuously about the periphery of the plug in register with a pump-well receiving and delivery port 24, which port establishes communication between the well and valve chamber 2'. The peripheral receiving and delivery groove 23 is connected to the receiving and delivery duct 17 by feed apertures 23', whereby the reservoir portion of the well is in constant communication with the inlet port 14.

From the foregoing description it is manifest that, with each revolution of the valve-plug, when the delivery groove 15 registers with the inlet port 14, oil will travel from the source of supply downwardly through the receiving and delivery duct 17 and from thence into the reservoir 6' of the well, being directed through the continuous peripheral groove 23 and receiving and delivery port 24. This feeding of oil to the reservoir extends through approximately one-quarter of a revolution of the plug, and, as the discharge port 15 passes the inlet port 14, communication is cut off from the source of supply. Following this cutting off of the supply to the reservoir the eccentric head 4 of the valve-plug will start to lift the pump piston 5 and approximately coincident to the lift of said piston the discharge groove 18 of the valve-plug will be brought into register with the discharge port 19. The piston will thus, in its lift, displace a pre-

determined quantity of oil from the reservoir 6', which oil will be forced through the receiving and delivery port 24, peripheral groove 23 and from thence upward through the receiving and delivery duct 17 and into the sight-feed basin, from which it will flow to the points desired to be lubricated. When the discharge groove 18 has passed the discharge port 19, the flow of oil will be cut off from the basin and this cutting off of the flow will be followed by retraction of the pump piston through its spring resistance to the position shown in Fig. 1 and thus the cycle is completed.

It is obvious that, should a smaller quantity of oil be required than that delivered by the maximum stroke of the piston, the said piston can be adjusted upwardly in such manner that its bottom face will only engage the eccentric face of the head 4 through a partial rotation of the latter. Hence it is apparent that predetermined measured quantities of oil are forced to their point of distribution and the supply is maintained by gravity from the inlet port 14.

I claim:

1. An oil-distributing mechanism comprising a housing having a chamber therein provided with an inlet port and a discharge port upon different planes, the said housing being also provided with a well and a receiving and delivery port communicating with said well and chamber, a rotatory valve-plug mounted in the chamber having a cored longitudinally disposed receiving and delivery duct, and a peripheral segmental delivery groove for registration with the inlet port and a peripheral discharge groove for registration with the discharge port together with an uninterrupted receiving and delivery groove for registration with the pump-well receiving and delivery port, each of which grooves communicate with the receiving and delivery duct, a spring-controlled pump-piston mounted in the well below the receiving and delivery port, and actuating means carried by the valve-plug for imparting motion to the pump piston.

2. An oil-distributing mechanism comprising a housing having a chamber therein provided with an inlet port and a discharge port upon different planes, the said housing being also provided with a well and a receiving and delivery port communicating with said well and chamber, a rotatory valve-plug mounted in the chamber having a cored longitudinally disposed receiving and delivery duct, and a peripheral segmental delivery groove for registration with the inlet port and a peripheral discharge groove for registration with the discharge port together with an uninterrupted receiving and delivery groove for registration with the pump-well receiving and delivery port, each of

- which grooves communicate with the receiving and delivery duct, a spring-controlled pump-piston mounted in the well below the receiving and delivery port, and an eccentric head carried by the valve-plug engageable with the pump-piston.
3. An oil-distributing mechanism comprising a housing having a chamber therein provided with an inlet port and a discharge port upon different planes, the said housing being also provided with a well and a receiving and delivery port communicating with said well and chamber, a rotatory valve-plug mounted in the chamber having a cored longitudinally disposed receiving and delivery duct, and a peripheral segmental delivery groove for registration with the inlet port and a peripheral discharge groove for registration with the discharge port together with an uninterrupted receiving and delivery groove for registration with the pump-well receiving and delivery port, each of which grooves communicate with the receiving and delivery duct, a spring-controlled pump-piston mounted in the well below the receiving and delivery port, actuating means carried by the valve-plug for imparting motion to the pump piston, and means for adjusting the stroke of the pump-piston.
4. An oil-distributing mechanism comprising a housing having a chamber therein provided with an inlet port and a discharge port upon different planes, the said housing being also provided with a well and a receiving and delivery port communicating with said well and chamber, a rotatory valve-plug mounted in the chamber having a cored longitudinally disposed receiving and delivery duct, and a peripheral segmental delivery groove for registration with the inlet port and a peripheral discharge groove for registration with the discharge port together with an uninterrupted receiving and delivery groove for registration with the pump-well receiving and delivery port, each of which grooves communicate with the receiving and delivery duct, a spring-controlled pump-piston mounted in the well below the receiving and delivery port, an eccentric carried by the valve-plug for engagement with an end of the pump-piston, means engageable with the ends of said pump piston for adjusting the stroke of the same, and a worm geared driving means for the aforesaid valve-plug.
- In testimony that I claim the foregoing I have hereunto set my hand at Milwaukee, in the county of Milwaukee and State of Wisconsin, in the presence of two witnesses.
